UNITED STATES PATENT OFFICE.

WILLIAM C. STARKEY, OF MANSFIELD, OHIO.

RATCHET MECHANISM.

1,145,709.

Specification of Letters Patent.

Patented July 6, 1915.

Application filed March 25, 1912. Serial No. 686,201.

To all whom it may concern:

Be it known that I, WILLIAM C. STARKEY, of Mansfield, county of Richland, and State of Ohio, have invented a certain new and useful Ratchet Mechanism; and I do hereby declare that the following is a full, clear, and exact description thereof, reference being had to the accompanying drawings.

The object of this invention is to provide an improved ratchet mechanism adapted particularly for use in signal apparatus for electrical and steam railway crossings, said signal apparatus having means for operating an electric switch situated on each side 10 of the crossing and at a distance from the crossing and arranged so that a car moving in either direction will operate the first switch to start the signal and the last switch to stop the signal. There is also a double 15 acting switch located at the crossing which is capable of stopping the signal when the car is going in either direction. This double acting switch at the crossing is not necessary but it is convenient as it stops the signal as the car reaches a crossing, whereas, 20 in the other form, without such middle switch, the signal continues after the car is past the crossing until it reaches the next switch located, say, a quarter of a mile 25 away.

The operation of the signal is controlled by a magnetically operated counting mechanism or wheel which automatically continues the operating of the warning signals 30 as long as any cars are approaching within a predetermined distance of the crossing where the signal is located, and the signal is not stopped until the last car which is approaching the crossing, within such predetermined distance, has actually passed the crossing. In other words, each approaching car operates the counting wheel or means, one notch or step and if there be five cars within a predetermined distance of 35 the crossing, they will operate said counting wheel five notches, so that said counting wheel will be actuated by several cars at the same time and then the signal be maintained until they all pass. As a car passes, the counting wheel is turned back one notch, but it is still in signaling position until they all pass.

The nature of the invention will be understood from the accompanying drawings and the following description and claim.

In the drawings Figure 1 is a central vertical section through the signal apparatus.

Fig. 2 is a horizontal section through the electrical magnet operating switch mechanism on the signal apparatus drawn on a line slightly below the top of the box or 60 casing. Fig. 3 is a perspective view upon a large scale of one of the armatures for actuating the controlling mechanism of the signal circuit. Fig. 4 is a perspective view of the upper portion of the ratchet wheel 65 and the pivoted stop pawl.

In said signal apparatus there is a casing 16 which has in it two electro-magnets 40 and 41, and when either magnet is energized its armature 50 will be attracted, elevated 70 and actuated. These armatures are formed, as shown in Fig. 2, with a hinge-like member 51 that is secured to a casing 16, then the armature is pivoted to said hinge-like member or plate 51 so the armature which 75 is a plate will be vertically oscillated beneath the magnet. The two armatures are mounted on opposite sides of the casing 16 and their free ends project toward each other to the proximity of the counting or 80 ratchet wheel 52 that is secured on the shaft 53 which has bearings at its ends on the wall of the casing 16. The ends of the armature plates 50 are divided to form a pair of prongs or projections 150. They 85 extend on each side of the wheel 52. Upon each armature plate 50 a pawl-plate 54 is hinged or pivoted, as seen in Fig. 2, so as to partially overlap the projections 150 so said projections extend somewhat beyond 90 the plate 54. There is a stop loop 55 secured to the underside of the armature plate 50 and a stop bar 56 is secured to the upper side of said plate 50. Both stop arms 55 and 56 project beyond the ends of the armature. 95 The lower stop loop 55 is to limit the upper movement of the armature with reference to wheel 52 and the upper stop bar 56 is to limit the downward movement of the armature as it engages the shaft 53, see Figs. 2 100 and 6, also raises centering arm 60.

When one of the magnets is energized it will lift its armature 50 and the hinge-pawl 54 will engage a tooth on the wheel 52 and actuate the wheel one notch or other predetermined extent. The stop loop 55 will prevent the movement of the armature and wheel too far. The wheel is held in its actuated position by the stop-pawl 60, it being weighted on a rod pivoted at one end 110 to plate 61 which is secured to casing 16, and there is a saddle 62 secured to the pawl

60 which rides upon the wheel 52 and prevents its movement except when actuated by one of the pawl-plates 51.

I claim as my invention:

5 Apparatus including a ratchet, a plate pivotally mounted at a point on each side of the ratchet and projecting toward the ratchet and with the inner end thereof recessed so that the plate when moved will not actuate 10 the ratchet, a small plate pivoted upon each of the afore-mentioned plates and adapted to rest thereon over the recess therein so that when the large plate is elevated the

small plate thereon will engage the ratchet wheel and actuate the same but said plates 15 will permit rearward movement of the ratchet magnets for operating said plates, and means for limiting the movement of the ratchet.

In witness whereof, I have hereunto affixed my signature in the presence of the witnesses herein named.

WILLIAM C. STARKEY.
